UNITED STATES PATENT OFFICE.

WILLIAM P. MOSELEY, OF STAMFORD, CONNECTICUT, ASSIGNOR TO THE YALE & TOWNE MANUFACTURING COMPANY, OF STAMFORD, CONNECTICUT.

DIAL-LOCK STRUCTURE.

Application filed October 4, 1923. Serial No. 666,508.

To all whom it may concern:

Be it known that I, WILLIAM P. MOSELEY, a citizen of the United States, and resident of Stamford, in the county of Fairfield and

5 State of Connecticut, have invented certain new and useful Improvements in Dial-Lock Structures; and I do hereby declare the following to be a full, clear, and exact description of the invention, such as will enable 10 others skilled in the art to which it appertains to make and use the same.

This invention relates to improvements in dial locks,—one object of the invention being 15 to provide means for setting the combination and operating the lock even though the dial has been broken off in an attempt to open the lock by force.

A further object is to provide an improved lock for a safe, the dial for which can be 20 removed while the same is being transported from point to point, but which can be operated by authorized persons at the desired locations by an auxiliary dial as well as by the usual duplicate dial.

25 With these and other objects in view, the invention consists in certain novel features of construction and combinations of parts as hereinafter set forth and pointed out in the claims.

30 In the accompanying drawings,—

Figure 1 is a sectional view showing a dial lock structure embodying my invention, applied to a door.

Figure 2 is a face view of the same, and

35 Figures 3, 4, 5 and 6 are detail views.

In the drawing, a dial lock 1 (which may be of any desired structure) is shown secured to a door 2, and the setting dial is shown at 3, the dial ring being represented 40 at 4. The operating spindle 5 of the structure is preferably made of hardened steel and instead of causing said spindle to extend into the operating or setting dial as has heretofore been the practice, the said spindle

45 terminates in a head 6, the outer face of which is caused to lie approximately flush with the outer face of the door. The spindle head 6 is made conical in form and so seated in the door that the spindle will be prevented from being driven back into the lock in an attempt to operate the lock by force.

The face of the enlarged or headed end

of the spindle is provided with a series of setting marks forming an auxiliary dial 7 55 which may or may not agree with the marks on the setting dial 3. This dial 7 may be stamped on the end of the spindle or it may be applied thereto in any desired manner.

The dial 3 is provided with a central opening which receives a threaded hub 8, the inner end portion of which is somewhat enlarged as at 9 and mounted to turn within an annular flange 10 integral with the central portion of the dial ring 4. The enlarged portion 9 of the hub 8 also forms a shoulder 11 which engages a shoulder 12 in the central portion of the dial 3,—the free edge of the annular flange 10 also engaging said shoulder 12. The hub member 8 is 60 made with a central bore 8^a for the accommodation of a bolt 13, the head of which rests in a recessed seat in the outer end of said hub member and is normally covered by a cap 14 having a threaded portion to 65 screw into the central opening in the dial 3 and is provided with a knurled peripheral portion to permit its ready application or removal. The forward portion of the bolt 13 is threaded and screws into a socket 70 15 in the headed portion of the spindle 5. The inner end of this socket may be somewhat contracted as at 15^a and contains a hardened steel ball 16 (preferably driven thereinto) to obstruct or frustrate any attempt to 75 drill through the spindle while the dial 3 is removed.

The hub member 8 which constitutes a part of the dial 3 is provided with two pins 90 17 to enter sockets 18 in the spindle head and these pins and sockets instead of being located diametrically opposite each other are so located that the dial 3 can be applied in only one position, which is the proper one for operating the combination of the 95 lock.

To remove the dial from the lock, the knurled cap 14 will first be removed, after which the bolt or screw 13 will be withdrawn and the dial 3 released.

The lock may be operated by any authorized person, either by his knowledge of the auxiliary setting mark as provided by the auxiliary dial 7, or by the application of a suitable duplicate dial such as the dial 3.

The lock structure minus the setting dial

3 may be shipped to a customer, and setting dials 3 may be made in duplicate and may be shipped separately to the customer.

Slight changes might be made in the details of my invention without departing from the spirit thereof or limiting its scope, and hence I do not wish to restrict myself to the precise details herein set forth.

Having fully described my invention what I claim as new and desire to secure by Letters-Patent, is:

1. The combination with the spindle of a dial lock, of an auxiliary setting dial carried by said spindle, and a dial adapted for removable connection with said spindle, either of said dials being adapted for use to operate the lock.

2. The combination with the spindle of a dial lock, of a setting dial removably connected with said spindle, and a concealed setting dial carried by said spindle.

3. The combination with the spindle of a dial lock, and a setting dial adapted for removable connection with said spindle, of an auxiliary setting dial carried by said spindle and adapted to be concealed by the first mentioned dial.

4. The combination with the spindle of a dial lock, of an auxiliary dial carried by said spindle, an exposed setting dial concealing said auxiliary setting dial, and means removably connecting said exposed dial with the spindle.

5. The combination with a dial lock, and a setting dial, of a hardened steel spindle between said lock and setting dial, said spindle having a socket and a hardened steel member located in said socket.

6. The combination with a dial lock, of a spindle therefor provided thereon at one end

with a setting dial and having a socket, and a hardened steel member located in said socket.

7. The combination in a dial lock structure, of a lock spindle provided at its outer end with an auxiliary dial, an exposed setting dial concealing said auxiliary dial, and a threaded bolt removably connecting said exposed setting dial with said spindle.

8. The combination in a dial lock structure, of a lock spindle provided at its outer end with an auxiliary setting dial and having a threaded socket; an exposed dial having a central threaded bore, a hub threaded in said bore and constituting part of said exposed dial and having a central bore, a threaded bolt passing through the bore of said hub and entering the threaded socket in the spindle, and a removable cap concealing said hub and bolt.

9. The combination in a dial lock structure, of a lock spindle provided at one end with an auxiliary dial, an exposed dial concealing said auxiliary dial and provided with a hub, a threaded bolt passing through said hub and threaded into the spindle, and pins connecting said hub and spindle, said pins being carried by one of said parts and adapted to enter sockets in the other, said pins being so relatively located as to insure correct position of the exposed dial when the same is being applied to the spindle.

In testimony whereof, I have signed this specification in the presence of two subscribing witnesses:

WILLIAM P. MOSELEY.
